PANEL OR SWITCH BOX

George R. Smith, Richmond Heights, Mo., assignor to Wm. Wurdack Electric Manufacturing Company, St. Louis, Mo., a corporation of Missouri

Application March 20, 1942, Serial No. 435,531

4 Claims. (Cl. 292—7)

This invention relates generally to panel or switch boxes. More particularly, my invention relates to a certain new and useful improvement in locking means especially, though not exclusively, adapted for the doors of panel or switch boxes of the type shown in Letters Patent No. 1,967,523, of July 24, 1934, and has for its chief object the provision of readily installed and actuatable means for securely locking the door of such a switch-cabinet or box in closed position for withstanding the disrupting or opening force of a severe fuse-explosion or the like.

And with the above and other objects in view, my invention resides in the novel features of form, construction, arrangement, and combination of parts presently described and pointed out in the claims.

In the accompanying drawings (two sheets)—Figure 1 is a plan view of a panel or switch-box equipped with door-locking means embodying my invention, the several levers thereof being in projected or door-locking position;

Figure 2 is a longitudinal sectional view of the box and door-locking means taken approximately on the line 2—2, Figure 1;

Figure 3 is a transverse sectional view of the box and door-locking means taken approximately on the line 3—3, Figure 1;

Figure 4 is a fragmental plan view of the box, illustrating the door-locking levers in retracted or door-opening position;

Figure 5 is an enlarged detail sectional view taken approximately on the line 5—5, Figure 1;

Figure 6 is an enlarged detail sectional view taken approximately on the line 6—6, Figure 1;

Figure 7 is a plan view quite similar to Figure 1 of a slightly modified embodiment of my invention;

Figures 8 and 9 are detail transverse sectional views taken approximately on the lines 8—8 and 9—9, Figure 7, respectively;

Figure 10 is an enlarged fragmental plan view illustrating a slightly modified bar-accommodating bracket forming part of the door-locking means of my invention; and

Figures 11 and 12 are detail transverse and longitudinal sectional views, respectively, taken approximately on the respective lines 11—11 and 12—12, Figure 10.

Referring now more in detail and by reference characters to the drawings, which illustrate practical embodiments of my invention, the box or cabinet proper, generally designated A, is in form and structure substantially identical with the panel or switch-box shown and described in said

Letters Patent No. 1,967,523, issued on July 24, 1934, to William Wurdack, now deceased, for Panel or switch box. Reference to such letters patent is made for a full, detail description of the box or cabinet A. For present purposes, suffice to merely say that the box A is in the form of a preferably metallic rectangular shell or casting preferably open at its opposite ends to facilitate electrical connections and comprising a rear wall *a* and forwardly projecting side walls *b*.

The side walls *b* are preferably connected at one end by a cross angle-strip *1*, for purposes presently appearing, and at their forward margins are offset inwardly, as at *2*, as best seen in Figure 3, to accommodate the lateral side flanges *3* of a lid or door, designated B in Figures 1 to 6, both inclusive, B' in Figures 7 to 9, both inclusive, and B'' in Figures 10 to 12, both inclusive, which is constructed of suitable sheet-metallic material, is of a size to snugly and completely fit over and upon the free margins of the side walls *b*, and at its one end is provided with a lateral flange *4*, welded or otherwise fixed to which are opposed pivot-members *5* adapted to endwise project through registering openings provided for the purpose in the shell side walls *b* and in the lateral cover flanges *3*, as best seen in Figure 1, for swingably securing the particular lid to and upon shell A.

At suitable locations adjacent its opposite side margins and also adjacent its one end margin, the particular cover or lid B, B', or B'', as the case may be, is slotted, as at *6*, for accommodating, when in closed position over the shell A, slotted or apertured keepers *C* welded or otherwise fixed to, and projecting forwardly from, the shell walls *b* and the end strip *1*, and with which respective keepers *C*, the several locking levers *7*, *8*, and *9*, presently described, are adapted to engage.

At a suitable location within its area, preferably in its longitudinal and lateral center, the material of the particular lid or cover is offset, as at *b'*, and suitably fixed in, and upstanding from, the lid or door portion *b'*, is a pivot-stud *D*, upon which is pivotally mounted for oscillation a crank *E*, which latter preferably includes two registering leaves or members *e*, *e*, partially offset the one from the other to provide a space, as at *10*, therebetween for accommodating the respective inner ends of the levers *7*, *8*, and *9*, and engaging said respective ends of the levers *7*, *8*, and *9* and the leaves *e*, *e*, of the crank *E*, are preferably loosely fitting pins or studs *11*, *11*, for pivotally securing the crank *E* and the

levers 7, 8, 9, together. It may be here remarked that the several pins or studs 11 loosely rest and ride at their lower end in the actuation of crank E upon the cover-section b', and fitted and secured pivotally on the stud D to rest flatwise upon the upper crank leaf e and marginally over the several studs or pins 11, is a suitable washer 17 initially equipped with a bendable ear 17' adapted to be upset to project into and endwise fit within a recess or opening e' in the crank E for retaining the several pins or studs 11 in lever-pivoting engagement with the crank E.

The lever-pivoting studs 11 are annularly disposed approximately equidistantly the one from the other, and permanently fixed to and upon, and upstanding from, the particular lid or cover B, B', or B'', as the case may be, in respective registration longitudinally and laterally thereof for slidably accommodating the respective outer ends of the levers 7, 8, 9, are slotted guide-members or brackets 12, as in Figures 1 to 9, both inclusive, and 12^a, as in Figure 10, which are also in respective parallelism with the several slots 6. Each of the brackets 12 has its single upright wall w and each of the brackets 12^a has its inner upright wall w' suitably spaced inwardly upon the particular door or lid from the several slots 6, and each lever 7, 8, and 9 has a length to project at its free end through the slotted wall or walls of the brackets 12 and 12^a and the registering keepers C, as best seen in Figures 1, 3, 7, and 10, each of said levers being also provided in suitable adjacency to its free end with an upstanding abutment or boss 13 for engagement with the inner face of said specific walls of the respective brackets 12 or 12^a for purposes presently appearing.

Suitably located upon, and upstanding from, the lid B of Figures 1 to 6, both inclusive, is a fourth fixed apertured bracket 14, with which a like apertured member 15 fixed on the lever 8 is adapted to flatwise engage for limiting the oscillatory movement of the crank E to lever-projecting position and for jointly receiving the hasp of a lock 16 for preventing unauthorized opening of the door B. However, alternatively or selectively, the brackets 14 and 15 may be omitted, and the lid, as the lid B' in Figure 7, provided upon its upper face with a stop 15' for engagement by the crank E and one of the keepers, as C', and its co-operable bracket 12', as best seen in Figures 7 to 9, both inclusive, may be outwardly extended, as at x, x, and registrably apertured, as at y, y, to similarly receive the hasp of a lock 16' for limiting the oscillatory movement of the crank E to lever-projecting position and for preventing unauthorized opening of the particular lid or cover.

In use and operation, the crank E and the several levers 7, 8, 9, are so proportioned that, when said levers are retracted and crank E oscillated to the right, they will occupy the respective positions illustrated in Figure 4, the levers 8 and 9 being then substantially in parallel registration, the lever 7 being approximately or nearly at right-angles thereto, all said levers being withdrawn from the several keepers, but loosely supported at their free ends by, and for movement through, the mentioned walls of the brackets 12 or 12^a, as the case may be, all the several abutments 13 being shifted inwardly away from said bracket and the particular door being then freely swingable to open position.

Reversely, when the crank E is pivotally swung

or oscillated to the left, the respective levers 7, 8, and 9 will be pivotally shifted endwise outwardly through the brackets 12 or 12^a and into engagement with their respective keepers, such movement of the crank E being continued until interrupted by and under the engagement of the bracket 15 with the bracket 14 or of the crank E with the stud or stop 15', at which time the crank E and levers or bolts 7, 8, and 9 have moved past "dead-center" position, that is to say, the position in which the boss 13 and the pin 11 of each of the bolts are substantially in line with the stud D, and into so-called "over-center" position, that is to say, the position shown in Figures 1 and 7. However, in movement of the crank E to such off-center position, the bosses 13 first impinge the several respective brackets 12 or 12^a, as the case may be, and under such impinging engagement of the bosses 13 with said brackets as movement of the crank E in such direction is continued, the several levers 7, 8, and 9 are sprung or strained, as it may be said, with the result that, with the crank E so shifted to off-center position, the several levers 7, 8, 9, so shifted into engagement with the several keepers C, and the bosses 13 in lever-straining or springing impinging relation to the fixed brackets 12 or 12^a, the crank E is firmly retained in such off-center position and the door B securely locked or retained in closed position upon the shell A and capable of withstanding great and excessive opening pressures.

Having reference now particularly to Figures 10 to 12, both inclusive, the brackets 12^a are of U-shape in end elevation and are permanently fixed at their respective bights h flatwise upon the door B'' over the respective slots 6 with their walls w' and w'' presented outwardly. The bight h is slotted, as at s, in registration with the seats 6 for accommodating the several keepers C or C', and the bracket-walls w' and w'' are slotted in registration and for registration with the respective slots of the keepers for accommodating the projection therethrough of the respective ends 45 of the several levers 7, 8, and 9, the outer walls w'' of the respective brackets functioning in reinforcing the several levers in withstanding end-buckling or deformation under the disrupting force of an explosion within the shell A.

The structure has been found exceedingly efficient in the performance of its intended functions, and I might add that suitably mounted for shiftable movement on the lid B, is a handle F for shifting a block G and depending blades H from "off" to "on" and from "on" to "off" position, as in said Letters Patent No. 1,967,523 fully and in detail described.

It is to be understood that changes in the form, construction, arrangement, and combination of the several parts of the box and its door-locking means may be made and substituted for those herein shown and described without departing from the nature and principle of my invention.

Having thus described my invention, what I claim and desire to secure by Letters Patent is:

1. A switch-box door-locking assembly including, in combination, a crank for pivoted oscillation upon the door, a fixed rigid bracket on the door in spaced relation to the pivot of the crank and for registration with a fixed keeper on the box, a metallic latch-bolt having pivot connection with the crank and shiftable longitudinally and obliquely on actuation of the crank in one direction for endwise engaging the bracket and keeper, and co-operable members on the door and

latch latch-bolt adapted for impinging engagement as the latch-bolt is pivotally shifted to over-center position for springing the latch-bolt for releasably retaining the latch-bolt in door-locked position.

2. A switch-box door-locking assembly including, in combination, a crank for pivoted oscillation upon the door, a fixed rigid bracket on the door in spaced relation to the pivot of the crank and for registration with a fixed keeper on the box, a metallic latch-bolt having pivot connection with the crank and shiftable longitudinally and obliquely on actuation of the crank in one direction for endwise engaging the bracket and keeper, a rigid member upstanding from the door, and a rigid member upstanding from the latch-bolt for impinging engagement with said first rigid member as the latch-bolt is pivotally shifted to over-center position for springing the latch-bolt for releasably retaining the latch-bolt in door-locked position.

3. A switch-box door-locking assembly including, in combination, a crank for pivoted oscillation upon the door, a plurality of fixed rigid brackets on the door in fixed lateral relation one to the other and also in spaced longitudinal relation to the pivot of the crank and for registration with respective fixed keepers on the box, a plurality of metallic latch-bolts each having pivot connection with, and disposed in spaced circum-

ferential relation about the pivot of, the crank, the several bolts being shiftable longitudinally and obliquely on actuation of the crank in one direction for endwise engaging the respective registering brackets and keepers, and means comprising a rigid member upstanding from the door and a second rigid member upstanding from one of said latch-bolts for co-operable impinging engagement as the latch-bolts are pivotally shifted to over-center position for springing the respective latch-bolt for releasably retaining the several bolts in door-locked position.

4. A switch-box door-locking assembly including, in combination, a crank for pivoted oscillation upon the door, a fixed rigid bracket on the door in spaced relation to the pivot of the crank and for registration with a fixed keeper on the box, a metallic latch-bolt having pivot connection with the crank and shiftable longitudinally and obliquely on actuation of the crank in one direction for endwise engaging the bracket and keeper, a rigid member upstanding from the door, and a pin of circular cross-section mounted in the latch-bolt for impinging engagement with said first rigid member as the latch-bolt is pivotally shifted to over-center position for springing the latch-bolt for releasably retaining the latch-bolt in door-locked position.

GEORGE R. SMITH.
